By Attorney

UNITED STATES PATENT OFFICE.

PERRY B. JOHNSTON, OF DUNCAN, OKLAHOMA.

DESIGN FOR A RING, BROOCH, OR PIN.

58,386.

Specification for Design.

Patented July 12, 1921.

Application filed October 25, 1920. Serial No. 419,520. Term of patent 7 years.

To all whom it may concern:

Be it known that I, PERRY B. JOHNSTON, a citizen of the United States, residing at Duncan, in the county of Stephens and State of Oklahoma, have invented a new, original, and ornamental Design for a Ring, Brooch, or Pin, of which the following is a specification, reference being had to the accompanying drawing, forming part thereof.

The figure is a plan view of a finger ring, showing my new design.

I claim:

The ornamental design for a ring, brooch, or pin, as shown.

In testimony whereof I affix my signature.

PERRY B. JOHNSTON.
